UNITED STATES PATENT OFFICE.

MARTIN SWINTEK, OF EDDYVILLE, IOWA.

TRAVELING-SCREEN SUCTION NOZZLE.

Application filed February 17, 1922. Serial No. 537,321.

To all whom it may concern:

Be it known that I, MARTIN SWINTEK, a citizen of the United States of America, and resident of Eddyville, Wapello County, 5 Iowa, have invented a new and useful Traveling-Screen Suction Nozzle, of which the following is a specification.

The object of this invention is to provide improved means for screening the mouth of 10 a nozzle employed in sand-pumping apparatus or dredges, and removing large objects such as stones from said nozzle, which might otherwise clog the nozzle or pipes.

A further object of this invention is to 15 provide a traveling screen traversing the mouth of a suction nozzle and particularly means for supporting the screen in its travel across said mouth.

A further object of this invention is to 20 provide an improved construction for an arcuate track adapted to carry a screen in its travel across the mouth of a suction nozzle, and means for mounting said track relative to the nozzle.

25 A further object of this invention is to provide anti-friction means carried by the tracks for engagement with the traveling screen.

A further object of this invention is to 30 provide improved liners or wear plates for the track members, which are removable and replaceable.

With these and other objects in view, my invention consists in the construction, arrangement and combination of elements 35 hereinafter set forth, pointed out in my claims and illustrated by the accompanying drawing, in which—

Figure 1 is a side elevation showing a 40 nozzle and arcuate track devices embodying my invention. Figure 2 is a plan of the same, the traveling screen being omitted. Figure 3 is a longitudinal section on the line 3—3 of Figure 2. Figure 4 is a cross-section on the line 4—4 of Figure 2. Figures 5 and 45 6 are detail cross-sections, on an enlarged scale, on the lines 5—5 and 6—6 of Figure 3. Figure 7 is a detail cross-section, on an enlarged scale, on the line 7—7 of Figure 1.

The present invention relates to and is an 50 improvement on the devices illustrated, described and claimed in Letters Patent Number 1,426,616 granted to me August 22, 1922, to which reference is hereby made.

In the construction of the device as shown 55 a suitable frame is employed which is pivotally supported at one end in any desired

manner, as by a barge or the like employed in sand-pumping or dredging operations. Angle track members 10, 11 are carried by and longitudinally of the upper portion of 60 the frame, and channel track members 12, 13 by the lower portion thereof, and said track members carry a flexible traveling screen 14 adapted to be driven in any suitable manner. A pipe 15 is mounted centrally and longitudinally of the frame and is adapted to discharge sand and water at any suitable location provided, and is provided at its forward or free end with a flange 16. 65 A nozzle 17 is provided and is formed with a base flange 18 by which it is attached to the flange of the pipe 15. The frame is adapted to be adjusted in such manner on its pivotal support that the outer end of the nozzle 17 rests on the bed of a stream or 70 body of water from which sand or the like is to be removed by pumping. The top and bottom walls of the nozzle 17 terminate in rounded noses or lips 19, 20 respectively, which are substantially circular in cross-section, and the side walls of said nozzle project beyond said lips to form wings 21, 22, the outer margins of which preferably 75 are formed on arcs. A supporting plate 23 is formed on or fixed to and extends transversely of the top of the rear portion of the nozzle 17, and a similar plate 24 extends across below said nozzle, directly beneath the plate 23. Angular brackets 25, 26 are 80 mounted on and bolted to the upper supporting plate 23 and are oppositely arranged with their vertical members outermost, and similar brackets 27, 28 are similarly arranged on and depend from the lowermost supporting plate 24, the vertical members of 85 the brackets 27, 28 being slightly longer than the corresponding members of the brackets 25, 26. The bolts 29 which secure the brackets 25, 26, 27, 28 in place preferably pass through slotted holes 30 in the 90 plates 23, 24, as indicated by dotted lines in Figure 2, to permit some adjustment of the brackets relative to the longitudinal center of the device. The brackets 25, 26 are formed with central webs 31 which are apertured 95 and secured together by means of a strap 32 bolted thereto; and the brackets 27, 28 are formed with similar webs secured together by a strap 33. Each bracket 25, 26 is formed 100 on the inner face of its vertical member with a shoulder, ledge or flange 34 on which rests the forward end of an angle track member 105

10 or 11 and which is securely fastened to said bracket. Each bracket 27, 28 is formed on the inner face of its vertical member with a shoulder, ledge or flange 35 contacted by the forward end of a channel track member 13 or 14 secured in place thereon. Arcuate track members 36, 37 are provided and are suitably mounted in parallel spaced relation to form continuations of and a connection for the angle tracks 10, 11 and channel tracks 13, 14, one on each side of and extending around the free end of the nozzle 17, said arcuate track members being angular in cross-section throughout their lengths. The base members of the angular track members 36, 37 rest on and are secured at their upper terminals to shoulders, ledges or flanges 38 formed on the inner faces of the vertical members of the brackets 25, 26 respectively; and at their lower terminals contact with and are secured to similar shoulders, ledges or flanges 39 on the brackets 27, 28 respectively. The arrangement of the parts is such that the upper surfaces of the base members at the upper terminals of the arcuate track members abut and are flush with the upper surfaces of the base members of the angle track members 10, 11 respectively; and the lower surfaces of said base members at their lower terminals abut and are flush with the lower surfaces of the upper flanges of the channel track members 12, 13 respectively, so that a continuous smooth track is provided for the screen 14. The side walls of the nozzle 17 flare outwardly between their ends and the wings 21, 22 are parallel. Intermediate or curved portions of the arcuate track members 36, 37 contact inner faces of the wings 21, 22 respectively and are secured thereto as by bolts or rivets 40, and the curvature of the outer ends of said wings preferably coincides with the curvature of said track members.

The screen 14 in its travel runs on and around the tracks provided by the arcuate track members 36, 37, no gears or sprockets being provided for said screen at its outer end. The screen may be provided with projecting lugs 41 which serve to stir and agitate the sand or gravel bed and facilitate entrance to the nozzle and pipe in the pumping operation. The screen also serves to prevent entrance to the nozzle and pipe of any large and undesirable objects such as stones, sticks and lumps of clay, the lugs engaging and removing such objects away from the nozzle.

The base members of the arcuate tracks 36, 37 are subject to considerable friction and consequent wear by the dragging of the screen thereover, especially in the curved portions between their ends. To obviate this and provide a means for repair of worn parts, liners or wear strips 42, 43 are provided for each arcuate track member. The

base members of the arcuate tracks are rabbeted to receive the wear strips or liners 42, 43, which are held in place by bolts 44, whereby they may be removed and replaced. The track surfaces of the wear plates are of course flush with and form continuations of the track surfaces of the members in which they are mounted. Two wear plates are provided for each track member, each on an arc of approximately ninety degrees and adapted to be arranged end to end, so that they may be independently removed and replaced as required.

A number of anti-friction rollers may be provided in the arcuate track members 36, 37 for engagement with the traveling screen 14. In this instance three such are shown for each track member, one near its lower or initial end and two in its upper portion, where the greatest pulling strain is present on the screen. The rollers are designated by the numerals 45 and each extends through an aperture 46 in the vertical flange of the track member, being pivoted on a pin 47 carried by a bracket 48 mounted on the track member. The rollers 45 engage side margins of the screen 14 and tend to reduce the frictional contact with the track members.

I claim as my invention—

1. In a device of the class described, a nozzle, arcuate track members secured to and carried thereby, and a flexible screen adapted to travel on said track members across the mouth of said nozzle, said track members being rabbeted throughout their arcuate portions, and curved wear plates inserted in and separately removable and replaceable relative to the rabbets of said members and adapted to receive sliding contact of said screen.

2. In a device of the class described, a pipe, a nozzle fixed to and communicating therewith, brackets mounted on and rising from said nozzle, other brackets fixed to and depending from said nozzle, said brackets being independently adjustable in a direction transversely of said nozzle, track members arranged substantially parallel with the trend of said pipe and secured at their ends to said brackets, a pair of arcuate track members secured at their upper and lower terminals to said brackets and forming continuations of and connections between the first-named track members, said arcuate track members being fixed in their forward curved portions to the forward end of said nozzle, and a flexible screen adapted to travel on said track members across the mouth of said nozzle.

3. In a device of the class described, a nozzle, arcuate track members secured to and carried by said nozzle, a flexible screen adapted to travel on said track members across the mouth of said nozzle, said track members being angular in cross-section and

the screen adapted for sliding engagement with the bases thereof, and rollers pivotally mounted on the outstanding members of said tracks and adapted for engagement with the edges of said screen.

4. In a device of the class described, a track member angular in cross-section, a screen adapted for sliding engagement with the base flange of said track, a bracket

mounted on the outstanding flange of said track, a roller pivoted in said bracket, said outstanding flange being formed with an aperture through which said roller projects for engagement with an edge of said screen.

Signed at Eddyville, in the county of Wapello and State of Iowa, this 18 day of January, 1922.

MARTIN SWINTEK.
